POWER OUTLET PEDESTAL BOX

Merle A. Plummer, North Hollywood, Calif., assignor to
Myers Electric Products, Inc., Montebello, Calif.

Filed Aug. 4, 1972, Ser. No. 278,088

Term of patent 14 years

Int. Cl. D13—03

U.S. Cl. D26—5 R

FIG. 1 is a top front perspective view of my power outlet pedestal box showing my new design.

FIG. 2 is a side elevational view thereof.

FIG. 3 is a rear elevational view thereof.

FIG. 4 is a top plan view thereof.

I claim:

The ornamental design for a power outlet pedestal box, substantially as shown.
